UNITED STATES PATENT OFFICE.

FAY O. FARWELL, OF DUBUQUE, IOWA, ASSIGNOR TO THE ADAMS COMPANY,
OF SAME PLACE.

DESIGN FOR A STOVE-LINING.

SPECIFICATION forming part of Design No. 26,472, dated December 29, 1896.

Application filed November 27, 1896. Serial No. 613,696. Term of patent 14 years.

To all whom it may concern:

Be it known that I, FAY O. FARWELL, a citizen of the United States, residing at Dubuque, in the county of Dubuque and State of Iowa, have invented a certain new and original Design in Stove-Linings; and I do hereby declare the following to be a full, clear, and close description thereof.

My invention relates to a design for stove-linings, and the novel features thereof consist, essentially, in a panel sunken in a frame and having thereon rows of raised crescent-shaped bosses and the bosses in every alternate row turned in opposite direction.

The following specification, taken in connection with the accompanying drawings, will both describe and illustrate my design.

Figure 1 shows a perspective of the design; Fig. 2, a section through line X X of Fig. 1. In the drawings, A designates a panel surrounded by the frame E, into which frame

said panel is sunk. Secured to or integral with the panel are bosses B, which project out from the panel till their outer surfaces are in the same plane with the surface of the frame. These bosses B are of crescent shape, having their points *a* in every other row turn up, and in the alternate row the points *a* turn downward or in the opposite direction. The essential features are the sunken panel surrounded by the frame E and the raised crescent-shaped bosses set in said panel in the manner described.

What I claim is—

The design for stove-linings as described and shown in the drawings.

In testimony whereof I affix my signature in the presence of two witnesses.

FAY O. FARWELL.
